US0D1056201S

(12) **United States Design Patent** (10) **Patent No.:** **US D1,056,201 S**
(45) **Date of Patent:** **** Dec. 31, 2024**

(54) **ELBOW CONNECTOR**

(71) Applicant: **Fisher & Paykel Healthcare Limited**,
Auckland (NZ)

(72) Inventors: **Erik Robertus Scheirlinck**, Auckland
(NZ); **Man Hei Jade Kwong**, Auckland
(NZ)

(73) Assignee: **Fisher & Paykel Healthcare Limited**,
Auckland (NZ)

(**) Term: **15 Years**

(21) Appl. No.: **29/789,038**

(22) Filed: **Aug. 26, 2021**

Related U.S. Application Data

(60) Continuation of application No. 29/752,652, filed on Sep. 28, 2020, now Pat. No. Des. 932,004, which is a continuation of application No. 29/720,971, filed on Jan. 16, 2020, now Pat. No. Des. 901,004, which is a continuation of application No. 29/694,004, filed on Jun. 6, 2019, now Pat. No. Des. 876,617, which is a division of application No. 29/635,207, filed on Jan. 29, 2018, now Pat. No. Des. 856,510.

(57) **CLAIM**

The ornamental design for an elbow connector as shown and described.

DESCRIPTION

FIG. 1 is a top, front, and right side perspective view of an elbow connector embodying our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a cross-sectional view taken along line 8-8 of FIG. 7.

The broken lines in the drawings depict portions of the elbow connector that form no part of the claimed design.

1 Claim, 5 Drawing Sheets
